UNITED STATES PATENT OFFICE.

JOHN C. BRACKETT, OF PHILLIPSBURG, NEW JERSEY, ASSIGNOR TO INGERSOLL-RAND COMPANY, OF JERSEY CITY, NEW JERSEY, A CORPORATION OF NEW JERSEY.

COAL-CUTTING MACHINE.

Application filed May 16, 1924. Serial No. 713,700.

To all whom it may concern:

Be it known that I, JOHN C. BRACKETT, a citizen of the United States, and a resident of Phillipsburg, county of Warren, and State of New Jersey, have invented a certain Coal-Cutting Machine, of which the following is a specification, accompanied by drawings.

This invention relates to coal mining machinery, and more particularly to coal cutters of the turret type which operate against the coal by means of a cutter having an endless chain carrying teeth and adapted to cut a slot or channel in the face of the coal.

It is an object of this invention to enable the cutter bar to be swung in any desired direction or inclined or reversed by a mechanism which is simple in construction and easily operated and controlled. Another object of the invention is to simplify the construction of the operating mechanism for the cutter chain in order to produce higher efficiency and greater power.

Other objects and advantages of the invention will be in part obvious and in part pointed out hereinafter. In the drawings forming part of the specification and in which similar reference characters refer to similar parts,

Figure 1 is a side elevation of a turret coal cutting machine constructed in accordance with the practice of the invention;

Figure 2 is a longitudinal vertical section of the machine shown in Figure 1 showing the internal construction and arrangement of the parts; and

Figure 3 is a plan view of the machine, parts being broken away to show the internal construction of the driving gear.

The machine illustrated in the drawings comprises a car A provided at its front end with a column B for supporting the cutter bar mounting C. A cutter bar D is mounted on the head C and supports an endless chain E having projecting teeth F which are adapted to cut into the coal to form a slot or channel in the usual manner.

Preferably, the car A is propelled by an electric drive, as for instance, the motor G which is adapted to rotate the wheels H through the medium of suitable gear transmission. For slower speeds there is provided a pinion J on the motor shaft K engaging with the gear L on a counter shaft O having a pair of worms P at either end

meshing with the worm wheels Q keyed to the axles R upon which the wheels H are fixed. For propelling the car at higher speeds a higher gear ratio is provided by the gear S on the motor shaft K which is adapted to drive a smaller pinion T on the counter shaft O. Selection of the desired gear is accomplished by means of a lever U which is connected by means of a yoke V with a sliding jaw clutch W cooperating with the pinion J and gear S to connect one or the other as desired with the motor shaft K. Usually the higher gear is employed for propelling the machine about the mine from one room to another. The smaller gear, however, is used for propelling the machine forward when greater power is necessary, such as in "sumping" wherein the cutter bar D is forced forward into the face of the coal seam. The speed of the vehicle may also be controlled by a suitable rheostat controller box X situated at the back platform Y provided for the operator.

The column B which supports the cutter bar mounting C is, in this instance, a plunger which cooperates with a movable cylinder Z attached to the mounting C and is movable up and down on the column B through the medium of fluid pressure introduced into the cylinder Z by means of a pipe a associated with the discharge of a gear pump b preferably mounted on the car A and driven preferably directly from the motor shaft K. This arrangement provides a means for raising and lowering the mounting C locating the cutter bar D at any desired height within the limits of the movement of the cylinder Z on the column B. The gear pump b may be operated continuously, its discharge of oil or other suitable fluid being conducted by a supply pipe c to a three-way valve d which in its normal position by-passes the oil back to the oil reservoir e through a by-pass pipe f. In the alternate position of the valve d the supply of oil is conducted from the supply pipe c to the pipe a and thence into the interior of the cylinder Z. When the valve is turned to a third position, the oil within the cylinder Z is returned due to the pressure caused by the weight of the cutter bar mounting C through the pipe a back through the valve d and the by-pass f to the reservoir permitting the cutter bar mounting to lower by gravity. In order to prevent the cylinder

Z from rotating with respect to the column B there may be provided projecting keys *g* attached to the column B which fit into grooves *h* on the inner surface of the cylinder. The packing *j* between the column B and the cylinder Z is preferably held in place on the cylinder Z by means of a ring *k* secured in any suitable manner on the bottom flange *o* of the cylinder.

10 The cutter bar mounting C is supported on a boss *p* preferably cylindrical and held thereon by means of a plate *q* bolted or otherwise secured to the boss. The portion *r* of the mounting C which fits on to the 15 boss *p* is provided with a cylindrical aperture fitting the boss so that the mounting C may rotate in a vertical plane. Such rotation is controlled by means of a worm wheel *s* formed integrally with the portions 20 *r* and cooperating with a worm *t* mounted on the cylinder Z. The hand wheel *u* which, if desired, may be provided with suitable reduction gearing *u'*, provides means for 25 rotating the worm *t* whereby the mounting C is turned to the desired angle and proper inclination.

The cutter bar D is offset from the boss *p* so that when it is desired to channel close to the floor, the mounting C is reversed by 30 rotation about the boss *p* and in such position the cutter bar D may operate very close to the floor without obstruction on the part of any of the parts of the machine. Also, when it is desired to cut close to the roof, 35 the mounting C may be turned so that the cutter bar D lies horizontally above the column B and projects forwardly, no obstruction being provided by any other part of the machine to the cutting directly on a 40 level with the roof. With the aid of the worm *t* and the worm wheel *s* the cutter bar D may also shear through the coal whether vertical or inclined in other directions.

The cutter bar mounting C includes a casting *v* which houses a driving motor *w* and suitable reduction gearing including the pinion *x* and the gear *y* for driving the chain sprocket *z* by which the motion of the cutting chain E is caused. The motor *w* 45 may be controlled in any suitable manner, as for instance, by means of the controller rheostat 2 mounted on the car A.

In operating the machine for cutting coal, it is commonly the practice to swing the 50 cutter bar D through an arc in this manner forcing the cutter bar sidewise into the coal. For this purpose the motor *w* is rotatable within the mounting C. The lower portion 55 of the motor casing supports a pinion 4 which is supported at its upper bearing by a gear case 5 pivotally attached to the casting of the motor *w*. The pinion 4 meshes with teeth 6 cut in the periphery of the mounting C and is driven by a worm wheel 60 65 7' meshing with the worm 7 which by

means of a jaw clutch 8 is in turn driven by a worm wheel 9 meshing with a worm 10 on the shaft 11 of the motor *w*. The clutch 8 is adapted to be controlled by means of a yoke 12 attached to a pivoted lever 13. 70 Thus, when it is desired to swing the cutter bar D, the clutch 8 is engaged whereupon the pinion 4 acting against the relatively stationary mounting C causes the motor *w* and the cutter bar D attached 75 thereto to swing laterally in the desired direction depending upon the direction of rotation of the motor *w*.

In order that the cutter bar D may be 80 swung by hand in either direction, means are provided to disconnect the worm wheel 7' from the pinion 4 and to this end a jaw clutch 14 is provided to engage and disengage the worm wheel 7' from the shaft 85 of the pinion 4. A lever 15 is adapted to 90 operate the clutch 14.

I claim:

1. A coal cutter comprising the combination of a cutter bar, a cutter bar mounting, a column, fluid pressure operated means to support said cutter bar mounting adapted to be raised on said column, a motor for operating said cutter bar rotatably disposed on said mounting and supporting said cutter bar, and means adapted to rotate said motor 95 for swinging said cutter bar.

2. A coal cutter comprising the combination of a cutter bar, a cutter bar mounting, a column, fluid pressure operated means to support said cutter bar mounting adapted 100 to be raised on said column, a motor for operating said cutter bar rotatably disposed on said mounting and supporting said cutter bar, means adapted to rotate said motor for swinging said cutter bar, said means 105 comprising gear teeth on said mounting and gearing associated with said motor to be driven thereby.

3. A coal cutter comprising the combination of a cutter bar, a cutter bar mounting, an electric motor for operating said cutter bar rotatably supported in said mounting and adapted to rotate said cutter bar and means to rotate said motor in said mounting including gear teeth on said mounting, 110 a gear supported by said motor casing and driving connections associated with the shaft of said motor and said gear.

4. A coal cutter comprising the combination of a carriage, a column on said carriage, a cutter bar mounting adapted to be raised and lowered on said column, means for rotating said mounting about a horizontal axis with respect to said column, an electric motor for operating said cutter bar 125 in said mounting and rotatable therein, a cutter bar relatively fixed with respect to said motor and rotatable therewith and means for swinging said motor and cutter bar with respect to said mounting. 130

5. A coal cutter comprising the combination of a carriage, a column on said carriage, a cutter bar mounting adapted to be raised and lowered on said column, means for rotating said mounting about a horizontal axis with respect to said column, an electric motor in said mounting and rotatable therein, a cutter bar relatively fixed with respect

to said motor and rotatable therewith, and means for swinging said motor and cutter bar with respect to said mounting including gear connections with said motor and operable against said mounting. 10

In testimony whereof I have signed this specification.

JOHN C. BRACKETT.
